(57) **CLAIM**

The ornamental design for an air treatment apparatus, as shown and described.

DESCRIPTION

FIG. 1 is a perspective view of an air treatment apparatus according to the present invention;

FIG. 2 is a front elevational view of the air treatment apparatus of FIG. 1;

FIG. 3 is a right side elevational view of the air treatment apparatus of FIG. 1, the left side elevational view being a mirror image thereof;

FIG. 4 is a rear elevational view of the air treatment apparatus of FIG. 1;

FIG. 5 is a top plan view of the air treatment apparatus of FIG. 1;

FIG. 6 is a bottom plan view of the air treatment apparatus of FIG. 1;

FIG. 7 is a perspective view of an air treatment apparatus according to the present invention with a top portion removed for clarity of illustration;

FIG. 8 is a front elevational view of the air treatment apparatus of FIG. 7;

FIG. 9 is a right side elevational view of the air treatment apparatus of FIG. 7, the left side elevational view being a mirror image thereof;

FIG. 10 is a rear elevational view of the air treatment apparatus of FIG. 7;

FIG. 11 is a top plan view of the air treatment apparatus of FIG. 7; and,

FIG. 12 is a bottom plan view of the air treatment apparatus of FIG. 7.

The broken lines are for illustrative purposes only and form no part of the claimed design.
